B. Singen, Atty.

UNITED STATES PATENT OFFICE.

DENIS FRANCIS DOWNES, OF COBURG, NEAR MELBOURNE, VICTORIA, AUSTRALIA.

SWITCH LOCK FOR MOTOR VEHICLES.

Original application filed April 12, 1920, Serial No. 373,292. Divided and this application filed August 31, 1921. Serial No. 497,343.

To all whom it may concern:

Be it known that I, DENIS FRANCIS DOWNES, a subject of the King of Great Britain, residing at 31 Coburg Street, Coburg, near Melbourne, in the State of Victoria, Commonwealth of Australia, have invented new and useful Improvements in Switch Locks for Motor Vehicles, of which the following is a specification.

10 This invention relates to improvements in means for use in locking motor-vehicles against unauthorized use and interference. The present application is a division of my application filed 12th April, 1920, Serial 15 Number 373,292.

Switch-locks as now commonly employed do not afford adequate protection against loss of or unauthorized use or interference with the vehicles to which they are applied, 20 by reason of being mounted upon the face-board in such manner that the latter can be sawn through, when the switch is readily removable and the wires can be re-connected, only requiring for such purpose the 25 use of tools of simple character.

The present invention provides a switch locking device which is operable by a key, whereby the ignition circuit is broken and is locked against re-making, said locking 30 device being characterized by having its principal functional elements fitted to the engine side of the dashboard, and by the provision of protective metal strips interposed between said dashboard and said lock 35 and switch.

The invention is illustrated in the accompanying drawings wherein:—

Figure 1 is a view in sectional elevation, and

40 Figure 2 is a sectional end elevation.

In these views the numeral 4 designates the dashboard of a motor-car upon which the switch locking device is mounted.

Fitted to the engine side 5 of the dashboard are two strips 6 and 7 of sheet metal, 45 one of which is preferably thinner than the other. These metal strips are for protective purposes to ensure the safety of the device, as in the event of an attempt being made 50 to cut it out by sawing through the dashboard, the two strips of sheet metal will break a saw blade used for such purpose.

A metal bracket 8 is fitted to the engine side of the dashboard by means of screws 9 passing through said protective strips 6 and 7.

55 A snap-switch 10 of ordinary construction is carried by said bracket 8, and to the finger ball of the switch operating lever 11 an extension or arm 12 is secured as by 60 means of a screw 13.

The arm 12 is affixed to the inner side of a barrel 14 of an ordinary pin and barrel lock 15 adapted to be operated by means of the well-known fluted and serrated 65 key 16.

This lock 15 is secured on the engine side of the dashboard by screws 17 or the like fastenings passing through said plates 6 and 7, the base of the bracket 8 and lugs 18 on 70 the barrel of said lock.

The switch 10 is furnished with a protective casing or cover 19. Holes 20 are formed through the base of the bracket 8 and through the protective metal strips 6 and 75 7 to accommodate the arm 12 connecting the barrel of the lock with the switch-operating lever.

The key 16 cannot be withdrawn from the lock 15 until the switch has been placed 80 at the "off" position.

Having now described my invention what I claim as new and desire to secure by Letters Patent is:—

In a device for locking a motor-vehicle 85 against unauthorized use and interference, an ignition-control switch mounted on the engine side of the instrument board of the vehicle and having an operating lever provided with a ball, a lock secured on said 90 board adjacently to said switch, and a rotatable member in said lock, an arm connecting said rotatable member with the ball of the switch operating lever, and a plurality of protective strips interposed 95 between said dashboard and said lock and switch, substantially as described.

In testimony whereof I affix my signature in presence of two witnesses.

DENIS FRANCIS DOWNES.

Witnesses:

JAMES H. ANDERSON,
JUNE B. SYMES.
